UNITED STATES PATENT OFFICE

2,483,343

FLUID ACTUATED CONTROL MECHANISM

Robert K. Jeffrey, deceased, late of Bexley, Ohio,
by Florence H. C. Jeffrey, executrix, Bexley,
Ohio, assignor, by mesne assignments, to The
Jeffrey Manufacturing Company, a corpora-
tion of Ohio

Original application August 10, 1943, Serial No.
498,087, now Patent No. 2,452,760, dated No-
vember 2, 1948. Divided and this application
July 7, 1944, Serial No. 543,791

6 Claims. (CL 121—41)

1

This invention relates to rotary fluid pressure pumps of the tiltable swash plate type, and one of the objects of the invention is the provision of fluid pressure motor mechanism for varying the inclination of a tiltable swash plate of a rotary fluid pressure pump.

Another object of the invention is the provision of fluid pressure motor mechanism adapted to tilt the swash plate of a rotary fluid pressure pump, combined with manually operated valve mechanism to predetermine the tilted position of such swash plate.

Other objects of the invention will appear hereinafter, the novel features and combinations being set forth in the claims hereto appended.

This application is a division of the co-pending application of the aforesaid Robert K. Jeffrey, Serial No. 498,087, filed August 10, 1943, now Patent No. 2,452,760, dated November 2, 1948, for an improvement in Mining machines.

In the accompanying drawings,

Fig. 1 is a sectional elevation of a variable volume hydraulic pump with a manually set hydraulically actuated volume control device and balance cylinder connected thereto;

Fig. 2 is an elevation of the left-hand end of the unit illustrated in section in Fig. 1;

Fig. 3 is a sectional plan view taken of that portion of Fig. 1 back of the central horizontal shaft;

Fig. 4 is a sectional elevation of the upper right-hand portion of Fig. 2;

Fig. 5 is an elevational view of the right-hand upper portion of Fig. 2;

Fig. 6 is a sectional elevation taken in a plane at right angles to the upper central portion of Fig. 4;

Fig. 7 is a sectional elevation taken on the line 7—7 of Fig. 1, looking in the direction of the arrows;

Fig. 8 is a sectional elevation taken on the line 8—8 of Fig. 1, looking in the direction of the arrows;

Fig. 9 is a sectional bottom plan view taken on the line 9—9 of Fig. 7, looking upwardly in the direction of the arrows;

Fig. 10 is an enlarged sectional elevation of the manually set hydraulically actuated volume control device and balance cylinder shown in Fig. 1; and

Fig. 11 is a development of a portion of the interior of a valve sleeve and co-operating valve post.

The volume of oil delivered by the variable volume pump 64 is regulated by adjusting the

2

angle of tilt of a swash plate 69 (Fig. 1). A hydraulic motor 126 comprising a cylinder 127 and a plunger 128 is mounted in position to act on a roller 129 as shown in Fig. 1. The hydraulic motor 126 acts as a balancing motor and is always connected to the high pressure side of the circuit.

To a port 130 at the left-hand end of the cylinder 127 is connected a pipe 131. A pipe 132 branches to the left from pipe 131 as shown in Fig. 10. The pipe 132 is connected to a port 132' of a manually set hydraulically actuated volume control device 133 which is shown in sectional elevation in Fig. 10.

15 The volume control device 133 comprises a casing 134 which is rigidly secured to a base plate 135 to which is also rigidly secured the casing 136 of the pump 64 (Fig. 1). To the outer end of the casing 134 of the volume control device 133 is secured a bearing block 137 in which is journaled a core valve or post 138. To the outer end of the valve or post 138 is secured a handle 139. By means of the handle 139 the valve 138 may be rotated to various positions to secure adjustment of the tilt of the swash plate 69.

The casing 134 in reality constitutes a hydraulic cylinder because within the same is a piston 140 of a piston motor. Extending to the right from the central portion of the piston 140, 30 as viewed in Fig. 1, is a cylinder 141 closed at its right-hand end by a bearing block 142. Extending to the right from the central portion of the casing 134 is a cylinder 143 adapted to act as a tubular guide for a plunger 144 the outer end 35 of which is in engagement with a roller 129' mounted on the swash plate 69 diametrically opposite the roller 129.

The valve or post 138 is provided with two parallel longitudinal bores 145 and 146, each 40 closed at its ends but each in communication with a pair of spaced lateral ports or passageways 145' and 155, each pair of which is connected by a groove or channel as seen in Fig. 10. A port 132' communicates with an annular groove 147 in the end or bearing block 137. A port 148 at one end of the bore 145 is always in communication with this annular groove 147, as shown in Fig. 10.

High pressure oil flows through the pipe 131 to the port 130 at the left-hand end of the hydraulic motor 126, as viewed in Fig. 1. The pressure in the cylinder 127 on the plunger 128 tends to tilt the swash plate 69 away from central position, thus increasing the volume of flow from the pump 64. The flow will be at a minimum when the 55 parts occupy the positions shown in Figs. 1 and 10,

because the piston 140 is then in its extreme right-hand position where it is locked by the oil confined in chambers 151 and 154 of the volume control device 133. The piston 140 is confined to a rectilinear movement by a spline or key 152 between the cylinder 141 and the cylinder or tubular guide 143.

Within the cylinder 141 is a spiral groove 153 which extends substantially the full length thereof of making one complete convolution and connects chambers 151 and 154. The separate ports 145' and 155 for the bores 145 and 146, respectively, normally straddle this groove 153 and may selectively be brought into communication with the spiral groove 153 by opposite relative rectilinear or axial movements between cylinder 141 and core valve or post 138. When the core valve 138 is turned by means of the handle 139 until the port 155 communicates with the spiral groove 153, the chambers 151 and 154 will be in communication with the port 155 through the spiral groove 153 and will be vented through the bore 146, an annular groove 156, and a pipe 150' to a gear case or oil sump, not shown. The hydraulic motor 126 then acts to move its plunger 128 outwardly and at the same time due to the venting of the oil through the spiral groove 153 the plunger 144 will be retracted. The tilt of the swash plate 69 will thus be increased to effect an increase in the output volume of liquid pumped by the pump 64.

When motor 126 acting through swash plate 69 moves cylinder 141 to such extent that the spiral groove 153 is no longer in communication with the port 155 the pump 64 attains the output volume predetermined by the setting of the core valve 138. That is to say, as the piston 140 moves into the chamber 151, the port 155 moves away from the spiral groove 153 and the flow of liquid through the latter is discontinued. The liquid in the chambers 154 and 151 again becomes trapped because the vent connections of the chambers 151 and 154 through spiral groove 153 and port 155 to the sump are sealed. The swash plate 69 is held at its adjusted angle because plunger 144 can recede no further and motor 126 is always acting to rotate the swash plate 69 to apply pressure upon it. Thus the pump is confined to the output volume predetermined by the setting of the core valve 138.

Now in order to decrease the output volume of the pump 64, that is, to expand the volume control device 133 and to retract the piston 128 of motor 126, the core valve 138 is rotated until the high pressure oil port 145' is in communication with the spiral groove 153. Then oil under high pressure flows through the spiral groove 153 into the chambers 151 and 154 and acts upon the piston 140 and bearing block 142 to move the plunger 144 outwardly or to the right as seen in Fig. 1. At the same time high pressure oil acts on the plunger 128 of the motor 126 to move it to the right, but because the combined areas of the piston 140 and bearing block 142 is greater than the cross-sectional area of the plunger 128. Consequently the plunger 144 will be extended and the plunger 128 will be retracted, thereby effecting tilting of the swash plate 69 toward central position to decrease the output volume of the pump 64.

As the piston 140 moves the plunger 144 outwardly from the cylinder 143, the port 145' will be moved away from the spiral groove 153 and the flow of oil into the chambers 151 and 154 cut off, whereupon the oil in the chambers 151 and 154 will be locked to block or hold the piston 140,

as seen in Fig. 1, against movement to the left in the casing 134. The swash plate will thus be locked in adjusted position in accordance with the manual setting of the core valve 138.

Under normal or balanced conditions, as illustrated in Fig. 11, the ports 155 and 145' straddle spiral groove 153 with ports 155 and 145' so located that as post 138 is rotated from its "Full-on" position toward the "Full-off" position to decrease the normal pump output, the pressure port 145' moves toward the spiral groove 153 and the exhaust port 155 moves away from said spiral groove.

It will be seen that when the pressure port 145' opens into the spiral groove 153 as a result of such movement, high pressure oil will flow into the chambers 151 and 154 to cause the piston 140 to move upwardly until the sleeve 141 closes the port 145'. Thus the piston 140 will move upwardly as the post 138 is rotated from its "Full-on" position toward its "Full-off" position.

As fully shown and described in my parent Patent No. 2,452,760 above identified, the apparatus described in this application is employed in a hydraulic system which includes a valving system that is responsive to overload conditions of an electric driving motor and overload and underload conditions of the pressure of the hydraulic liquid in the high pressure portion of the hydraulic system.

When the apparatus herein shown and described is employed in the hydraulic system above referred to and an overload or high pressure condition occurs in the hydraulic system a pressure responsive valve connects the ports 130 and 132' of the hydraulic motor 126 and volume control device 133, respectively, and the pipe 150' to the output side of the pump 64. When the above mentioned pressure responsive valve connects the ports 130, 132' and pipe 150' to the output side of the pump 64 the pressure of the liquid in pipe 150' increases. It will be seen that when high pressure oil enters chambers 151 and 154 through check valve 170 and passageway 171, the piston 140 will be moved upwardly even though the port 145' be closed. When this occurs the exhaust port 155 will be placed in communication with the spiral groove 153 but because the passage 146 is also subjected to the pressure of the oil entering the chambers 151 and 154 from pipe 150' it is effectively sealed from the sump. When the overload condition in the hydraulic system has been relieved, and consequently the high pressure in pipe 150' removed, the oil in chambers 151 and 154 will flow or be exhausted through the spiral groove 153 and port 155 to the pipe 150' and to the sump, as previously described, to permit the piston 140 to move downwardly until the spiral groove 153 is again straddled by the ports 155 and 145'.

A single exception to the above description relating to the communication between the exhaust port 155 and the spiral groove 153 is when the post is set to the "Full-off" position. In this setting of the post the exhaust port 155, as viewed in Fig. 11, is positioned so far to the left that it does not meet the spiral groove. This because it is desired to lock the piston in the "Full-off" position by closing the exhaust port 155. The maximum angle through which post 138 can be rotated from the "Full-on" to the "Full-off" positions is preferably not over 180 degrees. The spiral groove 153 extends preferably through an angle of 360 degrees but not more. As viewed in Fig. 11, the pressure port 145' will be just below and near the top of the groove 153 when the post 138 is in the "Full-on" position.

As previously described under certain conditions high pressure oil is delivered to the exhaust pipe 150' of volume control device 133, whereupon oil will flow from the annular groove 156 past the check valve 170 and through the passageway 171 into the chamber 151. From the chamber 151 the oil will flow through the spiral groove 153 into the chamber 154. Consequently, hydraulic pressure will be exerted on both the bottom of the closure block 142 and the bottom of the piston 140. This will cause tilting of the swash plate 69 toward its central "Full-off" position, thereby decreasing the output volume of the pump 64. Under these conditions, port 155 will communicate with groove 153 regardless of the manual setting of post 138 except in case it also is in the "Full-off" position. Consequently when normal conditions are restored in the pump circuit and the pressure in pipe 150' is reduced or released, the pump will automatically return to its normal predetermined position as determined by the position of adjustable post 138.

It will be evident that during normal control the core valve 138 is rotated in one direction or the other, to adjust swash plate 69 to a desired position for a predetermined output volume of the pump 64 and the swash plate will be automatically hydraulically locked and held in adjusted position unless automatic reduction of its output volume is effected by an overload resulting in a build up of pressure in pipe 150'. After the overload condition is relieved the pump 64 will again discharge liquid at the output volume for which it was adjusted or any desired readjustment of the output volume of the pump may be effected by manually rotating the core valve 138.

Mechanism for indicating the delivery volume of the pump 64 is illustrated in Figs. 4, 5 and 6. The swash plate 69 carries an arcuate rack 267 with which meshes a pinion 268. The pinion 268 is secured to the inner end of a shaft 269 which is journaled in a bearing block 270. This bearing block may be detachably secured to the casing 136 by means of a cap screw, as shown in Fig. 4.

Secured to the outer end of the shaft 269 is a pointer 271 movable over a scale on a plate 272 as shown in Fig. 5. When the swash plate 69 is centered as shown in Fig. 1, the pointer 271 should be at the designation indicating zero volume of pump delivery. When the swash plate is tilted to its maximum extent the pointer 271 will be moved clockwise, as viewed in Fig. 5, until it reaches the last designation on the scale.

The swash plate 69 may be provided with diametrically opposite extension pivot plates 273 each adapted to be journaled on a trunnion one of which is shown at 274 in the sectional plan view in Fig. 3. These trunnions are carried by supports one of which is shown at 275 in Fig. 3 fitting into a side opening in the casing 136 and secured to the latter by means of cap screws 276. It will thus be seen that the swash plate 69 is tiltable on a horizontal transverse axis which lies in a horizontal plane intermediate the pivotal axes of the rollers 129, 129'.

Journalized in the ends of the casing 136 is a shaft 68 to which is keyed a cylinder block 277 having a plurality of cylinders 278 in which are adapted to reciprocate pistons 279 each of which is urged by means of springs (Fig. 1) to have its outer end impinge against a ring 280 mounted on the swash plate 69.

In end plate 281 are two separate ports 282, 283 which are respectively in communication with ports 284 and 285, as shown in Figs. 2 and 7. Of

the ports 284, 285, one is the inlet and the other the outlet for the pump 64. The left-hand ends of the cylinders 278 are provided with arcuate ports 286 as shown in Figs. 1 and 8. The cylinder block 277 is driven by means of an electric driving motor, coupled to the splined end 37' of the shaft 68.

Obviously those skilled in the art may make various changes in the details and arrangement of parts without departing from the spirit and scope of the invention as defined by the claims hereto appended, and it is therefore wished not to be restricted to the precise construction herein disclosed.

Having thus described and shown an embodiment of the invention, what is desired to be secured by Letters Patent of the United States is:

1. Fluid actuated mechanism including in combination a cylinder, a piston in said cylinder cooperating therewith to form a closed expandable working chamber, said piston having an axially extending bore including a spiral groove connected with said chamber, a rotatable cylindrical member having spaced inlet and exhaust ports cooperating with said bore to form a valve, said ports normally straddling said spiral groove to trap hydraulic fluid in said working chamber for locking said piston against movement in one direction, a conduit connecting one of said ports with said chamber, and valve means in said conduit automatically operative in response to a predetermined pressure therein to control independently of said rotary valve means the increase in quantity of fluid in said closed expandable working chamber.

2. Fluid actuated mechanism including in combination a cylinder member, a piston member in said cylinder member cooperating therewith to form a closed expandable working chamber, said piston member having an axially extending bore, a cylindrical member rotatable and reciprocable in said bore, one of said members having a spiral groove opening into said chamber and the other of said members having spaced inlet and exhaust ports constructed and arranged to straddle normally said spiral groove to trap hydraulic fluid in said working chamber for locking said piston against movement in one direction, a conduit connecting one of said ports with said working chamber, and valve means in said conduit automatically operative in response to a predetermined pressure therein to control independently of said ports and groove the increase in quantity of hydraulic fluid present in said closed expandable working chamber.

3. Fluid actuated mechanism including in combination means forming an expandable fluid chamber including a cylinder member and a piston member movable relative to one another, means associated with said first named means forming an adjustable valve for setting the normal relative positions of said members, said valve including a spiral groove connected with said fluid chamber and movable with one of said members and spaced inlet and exhaust ports movable with the other of said members, said spiral groove and ports being shiftable relative to one another to admit to or exhaust hydraulic fluid from said expandable chamber to cause said members to reciprocate relative to one another in response to adjustment of said valve, said ports normally straddling said spiral groove, said inlet and exhaust ports being constructed and arranged in such manner that one of said ports is at all times in communication with said spiral groove when

said members are adjusted to operative positions relative to one another and are displaced from their normal relative position with respect to each other whereby said members will seek the normal position for which said valve is set, a conduit connecting one of said ports with said expandable chamber, and valve means in said conduit automatically operative in response to a predetermined pressure therein to control independently of said valve the increase in quantity of fluid in said expandable chamber.

4. Fluid actuated mechanism including in combination means forming an expandable fluid chamber including a cylinder member and a piston member movable relative to one another, means associated with said first named means forming an adjustable valve for setting the normal relative positions of said members, said valve including a spiral groove connected with said fluid chamber and movable with one of said members and spaced inlet and exhaust ports movable with the other of said members, said spiral groove and ports being shiftable relative to one another to admit to or exhaust hydraulic fluid from said expandable chamber to cause said members to reciprocate relative to one another in response to adjustment of said valve, said ports normally straddling said spiral groove, said inlet and exhaust ports being constructed and arranged in such manner that one of said ports is at all times in communication with said spiral groove when said members are adjusted to operative positions relative to one another and are displaced from their normal relative position with respect to each other whereby said members will seek the normal position for which said valve is set, a conduit connecting said exhaust port with said expandable chamber, and valve means in said conduit automatically operative in response to a predetermined pressure therein to control independently of said valve the increase in quantity of fluid in said expandable chamber.

5. Fluid actuated mechanism including in combination a cylinder, a piston in said cylinder cooperating therewith to form a closed expandable working chamber, said piston having an axial central bore including a spiral groove, a rotatable cylindrical member having spaced fluid inlet and exhaust ports and hydraulic pressure and exhaust conduits therein leading thereto extending into and cooperating with said bore to form a valve and a second working chamber, said spiral groove connecting said chambers and being normally straddled by said inlet and exhaust ports to trap hydraulic fluid in said working chambers for locking said piston against movement in one direction, the movable working area of said second mentioned chamber and the working area of

said piston being substantially equal to the total area defined by the diameter of said piston, conduit means connecting said exhaust conduit and said chambers, and valve means in said conduit means operative automatically upon a predetermined pressure in said exhaust conduit for admitting hydraulic fluid to said chambers independently of said valve.

6. Fluid actuated mechanism including in combination a cylinder, a piston in said cylinder cooperating therewith to form a closed expandable working chamber, said piston having an axial central bore including a spiral groove, a cylindrical member having spaced fluid inlet and exhaust ports adapted to be connected to a source of hydraulic fluid under pressure and to a fluid receiver respectively cooperating with said bore to form a valve and a second working chamber, said spiral groove connecting said chambers and being normally straddled by said inlet and exhaust ports to trap hydraulic fluid in said working chambers, the movable working area of said second mentioned chamber and the working area of said piston being substantially equal to the total area defined by the diameter of said piston, conduit means connecting one of said ports and said chambers, and valve means in said conduit means operative automatically upon a predetermined pressure in said one conduit for admitting hydraulic fluid to said chambers independently of said valve.

FLORENCE H. C. JEFFREY,
*Executrix of the Estate of Robert K. Jeffrey,
Deceased.*
